UNITED STATES PATENT OFFICE

143,728

DESIGN FOR A MEAT DISPLAY SEPARATOR

Howard H. Hall, Denver, Colo.

Application May 11, 1945, Serial No. 119,495

Term of patent 14 years

(Cl. D11—1)

To all whom it may concern:

Be it known that I, Howard H. Hall, a citizen of the United States, residing in the city and county of Denver and State of Colorado, have invented a new, original, and ornamental Design for Meat Display Separator, of which the following is a specification, reference being had to the accompanying drawing, forming part thereof.

In the drawing:

Figure 1 is a perspective view of a meat display separator showing my new design;

Figure 2 is an end view; and

Figure 3 is a side elevation thereof.

I claim:

The ornamental design for a meat display separator, as shown.

HOWARD H. HALL.
